DESIGN FOR A TEXTILE FABRIC

Curt Erwin Forstmann, Montclair, N. J.

Application January 5, 1935, Serial No. 54,736

Term of patent 14 years

To all whom it may concern:

Be it known that I, Curt Erwin Forstmann, a citizen of the United States, residing at Montclair, in the county of Essex and State of New Jersey, have invented a new, original, and ornamental Design for Textile Fabric, of which the following is a specification, reference being had to the accompanying drawing, forming part thereof.

In the drawing, the sole figure of which is a plan view of a piece of the textile fabric embodying the design of the present invention, the cloth depicted is of a single color.

The design comprises a lattice-like irregular configuration of a shaggy prominent outline, the definiteness of which lattice-like configuration is to an extent modified by its being composited with a field of vertical stria, the fabric presenting a dimple-like appearance.

I claim:

The ornamental design for textile fabric as shown and described.

CURT ERWIN FORSTMANN.
